(57) **CLAIM**

I claim the ornamental design for a spool holder for an embroidery sewing machine, as shown and described.

DESCRIPTION

FIG. 1 is a perspective view of a spool holder for an embroidery sewing machine;

FIG. 2 is a front elevational view thereof;

FIG. 3 is a rear elevational view thereof;

FIG. 4 is a top plan view thereof;

FIG. 5 is a right-side elevational view thereof; and,

FIG. 6 is an enlarged perspective view of the spool holder. The broken lines showing the unclaimed portions of the embroidery sewing machine are for illustrative purposes and form no part of the claimed design.

1 Claim, 3 Drawing Sheets
